UNITED STATES PATENT OFFICE

148,302

DESIGN FOR AN ILLUMINABLE SWITCH PLATE

Andrew C. Karlstad, Sherman Oaks, Calif., assignor to James L. Fouch, Inglewood, Calif.

Application September 9, 1946, Serial No. 133,190

Term of patent 14 years

(Cl. D26—13)

To all whom it may concern:

Be it known that I, Andrew C. Karlstad, a citizen of the United States, residing at Sherman Oaks, in the county of Los Angeles and State of California, have invented a new, original, and ornamental Design for an Illuminable Switch Plate, of which the following is a specification, reference being had to the accompanying drawings, forming a part thereof, wherein:

Fig. 1 is a front elevational view of the illuminable switch plate showing my new design;

Fig. 2 is a rear elevational view;

Fig. 3 is a vertical central cross-sectional view; and

Fig. 4 is a horizontal cross-sectional view.

The dominant features of the design reside in

the ornamental appearance of the front face of the switch plate shown.

I claim:

The ornamental design for an illuminable switch plate, as shown and described.

ANDREW C. KARLSTAD.
